SHUFFLEBOARD WEIGHT

Carmine Decepoli, Belleville, N.J.

Application October 18, 1949, Serial No. 122,101.

5 Claims. (Cl. 273—128)

1

My invention relates to an improvement in weighted discs of the type commonly employed in playing games upon a shuffleboard or other surface whereon the player by his skill seeks to slide such a disc or weight to a desired position.

One object of my invention is to provide an improved bottom surface for such a weight so that the weight in motion will follow a truer course with a minimum of frictional drag even though there be slight irregularities in the surface it passes over.

Another object is to provide improved means for clearly and attractively identifying such a weight even when it is some distance away from the observer.

Still another object is to furnish simple and effective means for holding larger identifying means in position on a weight under all conditions of use.

A further object is to provide for these additional advantages in a weight without unduly increasing manufacturing cost and without noticeably altering the conventional outline of a weight.

Other objects will appear from the description which follows.

In the drawings which illustrate the application of my invention to a shuffleboard weight:

Figure 1 is a top view of a weight embodying the improvement.

Figure 2 is a bottom view of the same weight.

Figure 3 is a cross sectional view through the center of the weight of Figures 1 and 2 with vertical dimensions in the bottom surface exaggerated for illustrative purposes.

Figure 4 is a similar cross sectional view illustrating a modification of the top recess equipped identifying means.

Figure 5 is a similar cross sectional view of the body member only illustrating a modification in the bottom surface.

Figure 6 is a similar cross sectional view of the body member only illustrating still another modification in the bottom surface.

Referring to the drawings in which the same number refers to the same or similar part, the weight shown consists basically of a discoid body member 1 having a circular depression or recess 2 in its top surface. Recess 2 may have any desired diameter but I prefer that its depth be as hereinafter described in detail.

In all of the illustrations shown the bottom surface of the weight has in its exact center, coincident with the vertical axis of the weight, apex 3 which is normally the point of contact between the weight and the surface of a shuffle-

2

In Figures 3 and 4 apex 3 surmounts a shallow cone whose slope 4 has been shown considerably exaggerated and distorted in the illustrations. Actually slope 4 would make an angle of from one to five degrees with the surface of the shuffleboard, and slope 4 would imperceptibly merge with apex 3 so that in reality apex 3 would present a smooth contact with the shuffleboard. The shallow cone referred to, as shown in Figures 3 and 4, has a base radius of approximately one-half of the radius of the bottom surface. Rising from the base of this shallow cone the bottom surface forms a ring or ridge 5 which lies in a plane a minute distance inward from the plane in which apex 3 lies. The difference in elevation between ridge 5 and apex 3 may be from .005 inch to .0010 inch. From ridge 5 to the periphery of the bottom surface such bottom surface slopes to form the frustum of a shallow cone.

10 The slope 16 from ridge 5 to the periphery of the bottom surface may be parallel to slope 4.

When the weight is slid across the board it normally balances on apex 3 but if it should tilt slightly or meet slight irregularities in the board, 15 surface it will bear on a portion of ridge 5 as well as upon apex 3. In my experiments with shuffleboard weights I find this two point contact under the conditions outlined to preserve the course of the weight and give better control to the player.

20 Figure 5 illustrates the same basic construction, namely, apex 3 has the point of contact with annular ridge 5 surrounding it as a supplementary point of contact since it lies in a plane minutely distant from the plane of apex 3. In Figure 5 the outer portion of the bottom surface is shown as the frustum of a shallow cone with slope 14 but the region between apex 3 and ridge 5 is shown as a surface formed by the sweep of a smooth curve about apex 3 merging with ridge 5 at its outer end and smoothly joining with apex 3.

25 Figure 6 again shows apex 3 as the sole point of contact when the ridge is horizontal with ridge 5, furnishing a point of contact if the weight is tilted. In this illustration ridge 5 is shown at the periphery of the bottom surface with curve surface 13 characterizing the area between apex 3 and ridge 5.

30 Other modifications may be made in that portion of the bottom surface lying between apex 3 and ridge 5 and likewise ridge 5 may be located at varying distances from apex 3.

35 The side wall of recess 2 is undercut as best 40 illustrated in Figures 3 to 6 inclusive and upon the bottom of recess 3 may be placed label 7

carrying a printed legend upon a selected color background. Made of heavy paper or cardboard label 7, with diameter equal to the diameter of the recess at its undercut portion, may be easily snap fitted into position. As a protection a transparent cover 8 of similar diameter may also be snap fitted into position as shown. Label 7 and cover 8 may, if desired, be cemented together although I find that when in position as later described they will be firmly held in place without being secured to each other. Label 7 and cover 8 are sometimes hereinafter referred to collectively as the display member.

As shown in Figure 3 split ring 9, of a size to completely fill the undercut of recess 2, is inserted into the recess and firmly holds the cover and label in position at the bottom of the recess.

Figure 4 shows a modification with respect to holding label 7 and cover 8 in place. In this modification a flexible transparent disc 10 slightly larger than the bottom of recess 2 is snap fitted in position. The peripheral margin of disc 10 bears against the overhanging portion of the wall of recess 2 as well as upon cover 8 and being in a flexed position constantly brings pressure to bear upon cover 8 and label 7.

To supplement the identification markings carried in recess 2 on label 7 annular groove 6 is cut into the peripheral surface of body member 1 a short distance below the top surface. In most cases shuffleboard weights have a peripheral surface that is convex and by placing groove 6 in the upper portion it is visible not only to an observer looking at the weight from the side but to an observer looking directly downward upon it as is shown in Figure 1.

Groove 6 is of such dimensions that the fingers of a player will not touch its internal surface. This surface may be painted with a paint of the same color that may be employed for the background of label 7. Thus each player may readily distinguish his weights, even from a distance, by the color of the paint in groove 6.

As heretofore stated, the depth of recess 2 is important. It is desired to have cover 8 or disc 10 so located from the top of body member 1 that a similar weight, shown as outline 11 in Figures 3 and 4, will not strike them. At the same time it is desired to have the recess as shallow as possible to make label 7 visible at as great a distance from the weight as possible. To secure the optimum depth I find such depth must be slightly greater than the sum of the thicknesses of label 7 and cover 8 (and disc 10 as the case may be) and the depth of a segment of a circle (having a radius equal to the radius of the maximum diameter of the weight) tangent to the top surface of the weight at two points lying on the diameter of the weight.

It is apparent that many changes and modifications may be made in the outlines of the weights which may employ my invention and that various features of construction illustrated may be used separately or in different combinations, all without departing from the spirit of my invention.

What I claim is:

1. A weight for a shuffleboard or the like comprising a discoid body member having a conical bottom with its apex projecting downward therefrom in the vertical axis of the body member and an annular ridge between the apex and the periphery of the conical bottom concentric with such apex lying in a plane that is located normal

to such vertical axis a minute distance upwards from the said apex.

2. A weight for a shuffleboard or the like comprising a discoid body member having a bottom surface dished upward and outward from a centrally located apex in its bottom surface to an annular ridge on the periphery of the bottom surface, the said annular ridge lying in a plane normal to the vertical axis of the weight a minute distance inward from the point.

3. A weight for a shuffleboard or the like comprising a discoid body member, a top surface, a circular recess in the top surface the bottom of which is surrounded by an undercut in its side wall, a display member seated within said recess and undercut and a bottom surface with an apex projecting downward therefrom in the vertical axis of the weight and an annular ridge concentric therewith lying in a plane that is located normal to such vertical axis a minute distance inward from the said apex such annular ridge also lying within the periphery of the bottom surface.

4. A shuffleboard weight comprising a discoid body member; a peripheral curved surface; a top surface; a circular recess in the top surface the bottom of which is surrounded by an undercut in its side wall; a display member seated in the bottom of the recess; the depth of the bottom of the recess below a line drawn on a diameter thereof and through the points of tangency of a described circle, of radius equal to the maximum radius of such discoid body member, with the edge of the recess where the line intersects the same, being slightly greater than the sum of the thickness of the display member and the depth of the segment of such circle lying below such line, and not more than the depth of a similarly formed segment by describing a circle, of radius equal to the minimum radius of such discoid body member, tangent to the edge of such recess.

5. A shuffleboard weight comprising a discoid body member; a peripheral curved surface; a top surface; a circular recess in the top surface the bottom of which is surrounded by an undercut in its side wall; a display member seated in the bottom of the recess; the depth of the bottom of the recess below a line drawn on a diameter thereof and through the points of tangency of a described circle, of radius equal to the maximum radius of such discoid body member, with the edge of the recess where the line intersects the same, being slightly greater than the sum of the thickness of the display member and the depth of the segment of such circle lying below such line.
